JOHN KRENACH, INVENTOR.

BY *Louis Hayka*

UNITED STATES PATENT OFFICE

2,253,336

BOTTLENECK

John Krenach, Detroit, Mich.

Application April 7, 1941, Serial No. 387,231

3 Claims. (Cl. 215—8)

The purpose of the invention is to provide a bottle in which a seal or a plurality of seals placed over the outlet may not be broken without leaving indications of its having been tampered with and in which a seal once broken cannot be replaced without breaking the neck of the bottle.

Another object of my invention is to provide a device of this character of simple construction and employing a combination of parts which are easy to make and easy to fit together.

A further purpose of my invention is to provide a bottle neck of the kind described and which does not call for any special means of closure nor for any special means of removing said closure of whatever type same may be.

I shall now describe my invention in detail with reference to the accompanying drawing, in which:

Fig. 1 shows a longitudinal sectional view through the neck of the bottle, said neck forming one part of my invention.

Fig. 2 is a longitudinal section through the neck of the bottle including my improvements therein.

Fig. 3 is a section taken on line 3—3 of Fig. 2.

Fig. 4 is a section taken on line 4—4 of Fig. 2.

Fig. 5 is a section taken on line 5—5 of Fig. 2.

Fig. 6 is a section taken on line 6—6 of Fig. 2.

Similar numerals refer to similar parts throughout the several views.

The neck of the bottle comprising my improvement is indicated by numeral 10 and is shown in detail in Fig. 1. It will be noted that this neck 10 is provided at some distance from its mouth 11a with an inner orifice or neck 11. The inner neck may be provided with an external thread 14 to receive a threaded cap 13, or it may be otherwise made suitable to receive an appropriate closure. Said neck 10 contains at its upper end, close to the mouth 11a, two diametrically opposed slots 12 on the inner wall of said neck 10, as shown, although obviously the number of said slots may be more than two. When it is intended to close the bottle, this may be done as above stated by means of a crown cap 13 which is fitted over the inner neck 11. The cap may be provided at the top with a depressed circular center 15 and a cross slot 16 to afford a hold for a tool employed for the purpose of unscrewing the cap. The line of demarcation of said circular center 15 is partly cut so that when desired the center may be pushed inwardly by a suitable tool, say, a screw-driver, a rod or some similar means. If preferred, the bottle may be closed by means of an ordinary cork 18.

In order to forestall tampering with the contents of the bottle, it is customary to place a seal over the closure in the mouth of the bottle and such a seal is indicated here by numeral 17. In Fig. 1 it is shown applied over a cork 18 in the neck 11, while in Fig. 2 it is shown applied over a crown cap 13. The seal may be made of paper or some other suitable material.

Up to this time I have been describing the 10 bottle and the means to close same, said neck of the bottle being as shown in Fig. 1. It is obvious that were the mouth 11a of the bottle neck left open, this would make the seal readily accessible and thus make it possible to tamper with same. In order to forestall this, I have devised a plug 20 which fits into the open neck of said bottle through said mouth 11a, in such a manner that the plug prevents tampering with the seal and yet does not prevent the bottle from being emptied when desired. Said plug 20 consists of a substantially hollow cylinder separated by a partition 21 into two chambers, a domed chamber 22 open at one end, and a chamber 23. A central opening 28 and a plurality of openings 29 surrounding same connects the two chambers. The upper chamber opens into outlet 24, which is of a diameter smaller than that of either of the chambers. The plug contains at least two pins 25, which are urged outwardly by coiled springs 26. When the plug is inserted into the neck 10 of the bottle, these pins 25, urged by springs 26, slip into slots 12 making it impossible to withdraw plug 20 from the neck 10 of the bottle. In order to secure a liquid-tight contact 15 between the neck 10 and the plug 20, I have banded the plug with two cork gaskets 27, one in the plane of the partition 21 and the other one close to the neck of the bottle, above the level of pins 25.

40 In order to complete the description of the plug, I want to add that projecting from the dome of said partition 21 into the lower chamber 22 are two or more sharp pointed prongs 30. Another seal 31, also made of paper or some other 45 suitable material, is placed in the lower chamber in a spaced relation to seal 17, which is placed right over the closure of the inner neck 11. The outer neck 11a may be suitably closed by a cap or cork, but I am not describing same as this 50 is no part of my invention.

I shall now describe the use of my invention: When the seals are in place and the plug has been inserted into neck 10 so that it is held thereby by means of pins 25, it is not possible to pour out the 55 contents of the bottle without breaking the seals.

Assuming that the inner neck 11 is closed by a cork, a corkscrew may be used for the purpose of withdrawing it from said neck 11, in which case the corkscrew would be extended towards the cork through the outlet 24 and through the central opening 28 in partition 21. In order to screw in said corkscrew into cork closure 18, both seals 31 and 17 would be broken. Then, when a hold upon the cork had been secured, it would be possible to pull out the cork so that its top would reach prongs 30. The prongs would cut into the body of the cork and prevent same from being rotated while the corkscrew was being withdrawn by rotation of the shank thereof. Otherwise, if it were not for the prongs, the rotation of the 15 corkscrew would also impart a rotary movement to the cork so that withdrawal of the corkscrew would not be possible without sufficient force to tear the texture of the cork. Because the cork in its withdrawn position would partly block the 20 central passage 28, the liquid contained in the bottle would be able to flow out through passages 29 into chamber 23 and then through mouth 24. In case the inner neck is closed by a cap, same could be unscrewed by inserting a screwdriver into the cross slot 16 and rotating the cap, or the 25 central portion 15 partly cut could be pressed in on the line of partly cut demarcation of said central portion. But again in order to reach the contents of the bottle, seals 17 and 31 would have 30 to be broken.

Once the bottle has been opened, as above described, it may again be closed by means of a cork stopper, cap or other means which may be applied to the mouth 24.

It will be seen that some slight changes may be introduced in this construction without departing from the spirit of my invention. What I, therefore, wish to claim is as follows:

1. In combination a cylindrical bottle neck including an inner orifice centrally located therein and adapted to be closed and sealed, and a

5 hollow cylindrical plug adapted to fit into said neck and divided by a transverse partition into a lower chamber to extend above said orifice, and an upper chamber leading to an outlet, said partition being provided with a plurality of openings connecting said chambers, projecting means on the plug, and corresponding slots on the inner surface of the neck to prevent the plug from being removed therefrom.

2. In combination a cylindrical bottle neck having slots on the inner surface thereof and including an axially located orifice spaced from the outer end of said neck, a hollow cylindrical plug adapted to fit into said neck, and comprising spring actuated radial projections to slip into said slots, a transverse partition to divide said plug into a lower chamber above said orifice, and an outer chamber leading to an outlet, said partition being provided with a plurality of openings, including one located centrally, and further provided with sharp prongs projecting downwardly into the lower chamber, a closure for the orifice, and a fragile sealing means over said closure.

3. In combination a cylindrical bottle neck provided with slots on its inner surface, and including an axially disposed orifice within said neck, but spaced from the outer end thereof, closure means for said orifice and fragile seal means over said closure means, a hollow cylindrical plug adapted to snugly fit into the neck, radial projecting pins on said plug to fit into said slots, annular cork gaskets on said plug to insure liquid-tight contact with the inner surface of said cylinder, said plug containing midway between its ends a partition perforated to afford passage for liquids, and provided with sharp prongs on its lower surface to check the rotary movement of the closure means, when said closure means has been moved out of engagement with the orifice.

JOHN KRENACH.
